UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS A CORPORATION OF ILLINOIS.

CAR SIDE CONSTRUCTION.

Application filed August 29, 1924. Serial No. 734,842.

My invention relates to improvements in car side construction.

It is an object of my invention to improve the construction of car sides formed of trussed construction and especially in the lower chord thereof.

It is another object of my invention to secure in a car side truss a lower chord which will be disposed partly above and partly below the floor line of the car.

It is also a particular object of my invention to secure in a car side truss a lower chord which will be adequately anchored to the transverse members of the underframe, and wherein the lower margin thereof is of great strength and rigidity to prevent buckling.

It is also a particular object of the invention to form in a car side truss the lower chord of two members and secure the same together thereby providing a truss, the lower part of which is of thicker material than the upper part thereof.

Further, my invention resides in certain improvements and details of construction such as will more fully appear hereinafter in the specification and claims.

In the drawing, Figure 1 is a side, elevational view of one-half of a car showing my improved construction, the other end of the car being a counterpart of that shown. Figure 2 is a vertical, transverse, sectional view showing on an enlarged scale that portion of the car construction which illustrates the construction of the lower chord and the connection thereof with one of the transverse members, said section being taken on a line corresponding substantially to the line 2-2 of Figure 1.

In said drawing the car is shown to include the side truss A, only one-half of the same being shown, as will be understood, floor B, transverse beams C, body bolster D, and end walls E. The side truss A of the car consists of vertical stakes 10 and corner bands 11, upper chord 12 preferably consisting of a bulb angle member and lower chord 13 preferably formed as indicated of two members 14 and 15 suitably riveted together at intervals by means of rivets 16, the lower of said members 15 is of angular shape and preferably consists of a bulb angle member having one flange 17 in engagement with the horizontal flange 18 of the transverse beam C and having the adjacent

flange 19 depending downwardly vertically below the top of the transverse beam and secured to the vertical flange 20 of the said transverse beam. The vertical flange 19 has the lower margin thereof formed with a short in-turned heavy flange 21 which constitutes the bulb portion of the bulb angle member 15. The beam C has a recess or cut-away portion 22 adapted to receive the said bulb portion 21 and to compensate for such a recess an angle 23 is employed connecting the stake 10 and the transverse beam C, the stakes 10 being extended below the level of the truss A, for the purpose of securing a suitable connection with the car underframe. Above the member 15 and resting on the same is the angle member 14 which is preferably formed with a long vertical flange 24 which extends upwardly above the floor line, while the adjacent flange 25 is securely riveted to the flange 17 of the bulb angle member by the rivets 16 as heretofore described and also by rivets which extend through the flange 18 of the beam C. The two members 14 and 15 thus together form a strong member of considerable depth to which the lower portion of the diagonal members 26, 27, 28 and 29 are secured both directly by means of rivets as indicated at 30, and by means of securing means 31 extending through the vertical stakes 10. A preferred manner of constructing the truss is to extend the lower portion of the diagonal members, as indicated at 32, somewhat below the level of the bottom chord and connect such portion with the downwardly extending portion of the side stakes 10. The connections of the upper portion of the diagonal members and vertical stake may be carried out in the usual manner common to this type of truss and as shown on the drawing.

The upper flange member 14 of the truss forms a convenient support for the floor B and the side planking 33 of the car. The double horizontal flange of the lower truss member as provided by the two members 14 and 15 forms an especially suitable lower chord for a car of the type shown, which is of the dump car type. The outer end of the floor door shown at 34 is adapted to be raised and lowered by means of the operating shaft 35, suitable connecting means being provided between the shaft and doors, as shown conventionally at 36. On such

cars, mainly due to a large portion of the floor area being devoted to dump doors, there is a tendency for the car to rack, and the use of a strong member suitably anchored at the floor line in the manner shown becomes of the greatest importance.

The combination of the two sections 14 and 15 in effect provides a lower side member which is substantially of T-shape and 10 with the double flanges disposed substantially at the floor and united to each other and to the transverse beams, these sections serve as a column of great strength to sustain the racking strains to which the car 15 is subjected in addition to the function which they exercise as the lower chord members of the trussed sides.

While I have shown the lower chord member in two pieces, it will be evident that the 20 equivalent of the two sections would be secured by a rolled unitary member, and I wish to include all constructions which come within the scope and spirit of the claims appended hereto.

25 What I claim is:

1. In a railway car, the combination with the transverse members of the underframe; of a trussed side including an upper chord, a lower chord, vertical members and diagonal members, said vertical members and diagonal members being extended downwardly below the lower chord and secured to the transverse members of the underframe and to the lower chord, said lower chord 35 having a horizontal flange in engagement with the cross-beams and having vertical portions extending above and below said horizontal flange.

2. In a railway car, the combination with 40 the floor of said car; of a trussed side including in its lower chord two angularly shaped beam members having horizontally disposed flanges placed back to back and arranged to support said floor, one of said 45 members having its vertically disposed flange extending outwardly of said trussed side and said floor, and the other of said members having a flange extending below the trussed side, said latter flange on its 50 lower extremity being provided with a bulb formation.

3. In a railway car, the combination with 55 the transverse beams; of a trussed side including an upper chord, a lower chord; vertical and diagonal members secured to said upper and lower chords, and to said transverse beams, said lower chord comprising two angular beam members having angular portions extending on the outer side of said 60 trussed side, and connected to said vertical and an angular portion extending below said trussed side, said latter angular portion being provided with an excess of metal along its lower extremity.

65 4. In a railway car, the combination with

transverse beams; of a truss side including a lower chord formed of two angle bars extending longitudinally the full length of the car side, and each having a flange arranged in horizontal position and disposed back to 70 back with reference to each other, and having vertically disposed flanges extending in opposite directions in a common vertical plane, the lower of said vertical flanges being reinforced by an outstanding marginal 75 portion of less extent than the remaining flanges of said chord, the horizontally arranged flanges being disposed inwardly with reference to the car side, the combined vertical width of said angle bars forming a 80 lower chord of restricted depth below the floor of the car as compared with the depth of said transverse beams.

5. In a railway car side, including fabricated elements forming a truss having a 85 lower chord comprising two angle-shaped beam members united together and extending longitudinally throughout the car side, one of said members being disposed above the other with their vertical flanges superposed in a common vertical plane, the lower beam member being in the form of a bulb angle member, said trussed elements being secured to the vertical flanges of both of 90 said members.

6. In a railway car truss side, the combination with the diagonal and vertical members of said side; of an upper chord; and a lower chord, said lower chord being formed of two vertically superposed angle bars, each 95 having a flange inwardly disposed with reference to the truss side in a horizontal direction, and being placed back to back, the vertical flanges of said members being superposed in a common vertical plane, and the 100 lower of said vertical flanges having a bulb formation forming the extreme lower margin of the lower chord, said diagonal and vertical members of the trussed side having their lower ends overlapped and secured to 105 the vertical flanges of both of the angle bars forming the lower chord.

7. In a railway car side, having vertically and diagonally disposed trussed members and a lower chord, the latter being formed 110 of two angle-shaped members secured together, one of said members being disposed above the other and the lower of said members consisting of a bulb angle bar with the bulb portion thereof defining the lower margin of said chord, the lower ends of said 115 trussed members being arranged in overlapping relation with each other and secured to the vertical flanges of each of said angle-shaped members.

8. In a railway car, the combination with a transverse beam, of a car side including: an upper chord, a lower chord and vertical stake members secured to said upper and lower chords and also to said transverse 120 125 130

beam, said lower chord comprising two angular members placed back to back and having adjacent flanges horizontally disposed and secured to each other and to the transverse beam, the upper of said angular members having a vertical flange extending upwardly above the top of the transverse beam and the other of said members having a vertical flange extended downwardly, said last named flange being provided with an excess of metal along its lower extremity, the vertical stake member being secured to the vertical flanges of both members and extended for an appreciable distance below the said extremity and secured to the transverse beam 15 member.

In witness that I claim the foregoing I have hereunto subscribed my name this 18th day of August 1924.

ARGYLE CAMPBELL.
